US00D878364S

(12) **United States Design Patent** (10) Patent No.: **US D878,364 S**
(45) Date of Patent: **** Mar. 17, 2020**

(54) **BODY OF SMART WATCH WITH HEALTH MONITOR SENSOR**

(71) Applicant: **Fitbit, Inc.**, San Francisco, CA (US)

(72) Inventors: **Anthony Gerald Kern**, Pleasant Hill, CA (US); **Yu Chuan Kang**, Taipei (TW); **Derek Jenchia Loh**, San Carlos, CA (US); **Benjamin Patrick Robert Jean Riot**, San Francisco, CA (US); **Irina Igorevna Kozlovskaya**, San Francisco, CA (US); **Jeffrey Andrew Fisher**, Mountain View, CA (US); **Patrick James Markan**, San Francisco, CA (US)

(73) Assignee: **Fitbit, Inc.**, San Francisco, CA (US)

(**) Term: **15 Years**

(21) Appl. No.: **29/664,595**

(22) Filed: **Sep. 26, 2018**

H04M 1/04; H04M 1/05; H04M 1/667; H04M 1/6058; Y02B 60/1217

CLAIM

The ornamental design for a body of a smart watch with health monitor sensor, as shown and described.

DESCRIPTION

FIG. 1 is a top, right side isometric view of our new design for a smart watch with health monitor sensor with wrist bands attached, in a first embodiment.

FIG. 2 is a top, left side isometric view of FIG. 1 with the bands removed from the body.

FIG. 3 is a top, left side isometric view of the body of the smart watch of FIG. 1.

FIG. 4 is a left side elevation view of FIG. 3.

FIG. 5 is a right side elevation view of FIG. 3.

FIG. 6 is a front side elevation view of FIG. 3.

FIG. 7 is a back side elevation view of FIG. 3.

FIG. 8 is a top plan view of FIG. 3.

FIG. 9 is a bottom plan view of FIG. 3.

FIG. 10 is a bottom, left side isometric view of FIG. 3.

FIG. 11 is a top, right side isometric view of our new design for the smart watch with health monitor sensor showing our new design, in a second embodiment.

FIG. 12 is a left side elevation view of FIG. 11.

FIG. 13 is a right side elevation view of FIG. 11.

FIG. 14 is a front side elevation view of FIG. 11.

FIG. 15 is a back side elevation view of FIG. 11.

FIG. 16 is a top plan view of FIG. 11.

FIG. 17 is a bottom plan view of FIG. 11; and,

FIG. 18 is a bottom, left side isometric view of FIG. 11.

The features shown in broken lines in the drawing depict environmental subject matter only, and form no part of the claimed design.
